PAIR OF SPECTACLES

David W. Johnsen, Southbridge, Mass., assignor to
American Optical Corporation, Southbridge, Mass.

Filed Aug. 20, 1973, Ser. No. 389,902

Term of patent 14 years

Int. Cl. D16—06

U.S. Cl. D57—1 F

FIG. 1

FIG. 2

FIG. 3

FIG. 1 is a front elevational view of a pair of spectacles embodying my new design. The temples have been omitted for convenience of illustration;

FIG. 2 is a top plan view thereof, the temples being broken away for convenience of illustration; and

FIG. 3 is a view from one side of the pair of spectacles, the opposite side being of substantially the same appearance.

I claim:

The ornamental design for a pair of spectacles, as shown and described.
